UNITED STATES PATENT OFFICE.

OSCAR T. GLASSCOCK AND WILLIAM F. PHILLIPS, OF SHAMROCK, TEXAS.

VALVE-LIFTER.

1,115,424.

Specification of Letters Patent. Patented Oct. 27, 1914.

Application filed June 6, 1914. Serial No. 843,470.

To all whom it may concern:

Be it known that we, OSCAR T. GLASSCOCK and WILLIAM F. PHILLIPS, citizens of the United States, and residing at Shamrock, 5 in the county of Wheeler and State of Texas, have invented new and useful Improvements in Valve-Lifters, of which the following is a specification.

The primary purpose of this invention is 10 the provision of an appliance for jacking up the valve spring of an internal combustion engine when it is required to remove the valve for any purpose.

The invention consists of a device embodying two standards, the one relatively stationary and the other movable, and manually operable means for actuating the movable standard and securing the same in adjusted position, said actuating means embodying an operating lever and a ratchet mechanism, the several parts involving a novel construction and arrangement whereby the power may be conveniently applied and the device capable of being easily and 20 readily fitted to the valve mechanism of internal combustion engines generally, to admit of the valve spring being compressed when it is required to release or secure the valve.

30 The invention consists of the novel features, details of construction and combination of parts, which hereinafter will be more particularly set forth, illustrated and claimed.

35 In the drawings hereto attached:—Figure 1 is a perspective view of a valve lifter embodying the invention. Fig. 2 is a side view partly in section. Fig. 3 is a horizontal section on the line $x-x$ of Fig. 2.

40 Corresponding and like parts are referred to in the following description, and indicated in all the views of the drawings, by the same reference characters.

The standard 1 is provided at its lower 45 end with an arm 2 which is adapted to engage the crank case or like part of the engine crane through which the push rod operates to engage the stem of the valve. The standard 1 is formed upon its rear side with 50 a plurality of teeth 3. A second standard 4 is slidable upon the standard 1 and has an arm 5 at its lower end for engaging the valve

spring when it is required to compress the same to admit of removing or placing the pin in position by means of which the valve 55 spring is confined in a manner well understood. The arms 2 and 5 are notched or forked at their extremities to fit around the parts such as the push rod bushing and valve stem when the device is in position. The 60 standards and arms may be formed in any manner. A bracket 6 is secured at one end to the standard 4 and its opposite end is formed with an opening to receive the standard 1, upon which it is free to slide. 65 A dog 7 is pivotally connected at one end to the upper end of the standard 4 and its opposite end has an opening formed therein through which the standard 1 passes freely. The dog 7 supplements the action of the 70 bracket 6 in retaining the standard 4 in place and directing the same in its movements upon the standard 1. The standard 4 is retained in the adjusted position by means of the dog 7 engaging one of the 75 teeth 3. A stop 8 provided upon the standard 4 is adapted to engage the dog 7 and limit the downward movement of such dog and cause it to rise with the standard 4 when the latter is elevated. 80

The operating lever 9 is connected at its inner end with the bracket 6 by means of a link 10 and stud 11. The inner end of the operating lever is forked and the forked members embrace opposite sides of the standard 1 and link 10, the terminal portions of the forked members being brought together upon opposite sides of the link 10 and secured thereto by means of a fastening 12. A slide 13 is mounted upon the standard 1 90 and the forked members of the operating lever 9 are pivoted to such slide by means of fastenings 14, which are preferably threaded to the said forked members, the inner ends of such fastenings entering openings formed in opposite sides of the bearings 14. A dog 15 is pivoted at its outer end to the operating lever 9 at 16 and its inner end is formed with an opening to receive the standard 1. 95

A spring 17 secured at one end to the operating lever 9 has its free end exerting a pressure upon the dog 15 to cause it to engage the teeth 3 of the standard 1. The 100

operating lever and slide 13 and dog 15 are arranged intermediate of the bracket 6 and dog 7.

In the operation of the device, the same is arranged so that the arm 2 engages the crank case or other part of the engine crane and the arm 5 is in engagement with the spring of the valve to be compressed. Upon depressing the outer end of the operating lever 9, the inner end of such lever is elevated thereby lifting the bracket 6 and standard 4. During this movement the dog 15 engages one of the teeth 3 and the operating lever turns about the pivot fastening 16, the slide 13 moving upward with the bracket 6 and standard 4. Should it be necessary to lift the outer end of the operating lever to bring it to a position to be again depressed for lifting the standard 4, and arm 5 to further compress the valve spring, the standard 4 is held in the elevated position by means of the dog 7 and during the upward movement of the outer end of the operating lever, both the slide 13 and dog 15 move upward upon the standard 1. When next depressing the outer end of the operating lever 9, the dog 15 remains stationary by reason of its engagement with one of the teeth 3 and the standard 4 and adjunctive parts are carried upward as in the first instance, the dog 7 moving upward with the standard 4 by reason of the engagement of the stop 8 therewith. By proper manipulation of the operating lever 9, the standard 4 is permitted to move downward upon the standard 1 thereby releasing the valve spring which may assume its normal position after the pin has been placed in position in the stem of the valve.

From the foregoing description, taken in connection with the accompanying drawings, the advantages of the construction and of the method of operation will be readily apparent to those skilled in the art to which the invention appertains, and while we have described the principle of operation of the invention together with the device which we now consider to be the best embodiment thereof, we desire to have it understood that the device shown is merely illustrative and that such changes may be made when desired as are within the scope of the invention as claimed.

It may be advantageous to connect the upper end of the standard 1 with a convenient part of the engine or frame, and for this purpose a short chain 18 is engaged at one end with the standard 1, and is provided at its opposite end with a hook 19 either to engage a part of the engine or frame or to engage one of the links of the chain 18 after an end portion of such chain has been passed around a suitable or convenient part of the frame.

Having thus described the invention, what is claimed as new is:—

1. In a device of the character specified, the combination of two standards, the one relatively fixed and the other movable upon the fixed standard, a dog pivotally connected with the movable standard and adapted to engage the fixed standard to hold the movable standard in the adjusted position, a slide mounted upon the fixed standard and an operating lever mounted upon such slide and having connection with the movable standard, and a dog pivoted to the operating lever and adapted to engage the fixed standard to support the operating lever when actuated to elevate the movable standard.

2. In a device of the character set forth, the combination of fixed and movable standards, a dog pivoted to the movable standard and adapted to engage the fixed standard to hold the movable standard in adjusted position, a stop upon the movable standard to engage the said dog to cause the same to move upward with the movable standard, a slide mounted upon the fixed standard and adapted to intermittently grip the same, an operating lever pivoted to such slide and having connection with the movable standard, and a dog pivoted to the operating lever and adapted to intermittently grip the fixed standard.

3. A device of the character set forth, the same comprising a toothed standard having an off-standing arm, a movable standard provided with an off-standing arm and slidable upon the toothed standard, a dog pivoted to the movable standard and slidable upon the toothed standard and adapted to engage the teeth thereof to hold the movable standard in adjusted position, a stop upon the movable standard to engage the said dog, a slide mounted upon the toothed standard and adapted to intermittently engage the teeth thereof, an operating lever mounted upon such slide and having connection with the movable standard, and a dog pivoted to the operating lever and slidable upon the toothed standard and adapted to engage the teeth thereof.

4. A device of the character set forth comprising a toothed standard having an off-standing arm, a movable standard having an off-standing arm and provided with a stop, a bracket extending from the movable standard and slidable upon the toothed standard, a dog pivoted to the movable standard and slidable upon the toothed standard and adapted to be engaged by the said stop, a slide mounted upon the toothed standard intermediate of the said bracket and dog, a lever having a bifurcated end embracing the toothed standard and slide and pivoted to the latter, a link connection

between the inner end of the operating lever and the movable standard, a dog pivoted to the operating lever and slidable upon the toothed standard and adapted to engage the 5 teeth thereof, and a spring for normally holding the dog of the operating lever in engagement with the toothed portion of the fixed standard.

In testimony whereof we affix our signatures in presence of two witnesses.

OSCAR T. GLASSCOCK.
WILLIAM F. PHILLIPS.
